UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

SOUND-MODIFYING DEVICE.

1,393,557.

Specification of Letters Patent. Patented Oct. 11, 1921.

Application filed March 18, 1918. Serial No. 223,181.

To all whom it may concern:

Be it known that I, JAMES L. MCQUARRIE, a citizen of the United States, residing at Montclair, in the county of Essex, State of New Jersey, have invented certain new and useful Improvements in Sound-Modifying Devices, of which the following is a full, clear, concise, and exact description.

This invention relates to means by which the sound produced by a phonograph diaphragm or other source of sound vibration is modified in order to produce a more pleasing effect, and it is directed more particularly to means by which the extent of the modification to which the produced sounds are subjected is selectively varied.

Phonographs in which an adjustable plug is mounted between the diaphragm and the outer end of horn or like sound conveying device, are well-known. This arrangement, however, requires that the person in charge of the phonograph be familiar with the record to be played and that he be somewhat expert in the manipulation of the plugging mechanism if smooth execution of the selection is to be obtained.

An object of the present invention is to provide an arrangement by which the adjustment of the sound modifying device is automatically controlled, so that the selection is always reproduced in the most satisfactory manner without depending on the skill or attentiveness of an attendant. Other objects and advantages will appear from the following detailed description, considered in connection with the accompanying drawings, in which Figure 1 is a view in vertical cross section of the sound box and associated parts of a phonograph in which the invention has been incorporated; Fig. 2 is a partial front view in elevation with the diaphragm removed and other parts broken away; and Fig. 3 is a perspective view, the greater part of the sound box being broken away.

In the arrangement shown in the drawing, the sound producing diaphragm 1 is mounted in a well-known manner in one end of the sound box 3, the other end of which has an opening 5 in alignment with the inner end of the horn or sound conveyer 7. Vibration of the diaphragm 1 is produced by suitable mechanism, such as a lever 9 carrying a stylus 11 arranged to travel in groove 13 of the record member 15. These

elements and arrangements may be replaced by other sound producing and conveying means, as will be readily understood by those skilled in the art concerned. In accordance with a preferred embodiment of the present invention, the opening 5 of the sound box 3 is surrounded by an inwardly projecting annular flange 17 upon which is fitted the member 19. Pins 21 projecting from the flange 17 through slots 23 in the member 19 hold the latter on the flange 17 while permitting it a limited rotary movement. The forward end of the member 19 comprises a conical head 25 provided with a number of circumferentially spaced openings 27.

Fitted in the apex of the conical head 25 is a bearing 29 through which extends the short shaft 31. On the inner end of this shaft is fixed a hollow conical member 33 having slots 35 which may be brought more or less into alignment with the slots 25 by rotating the shaft 31. The outer end of shaft 31 carries a laterally projecting pin 37 which slidably fits in the socket 39 carried on one end of the spring held lever 41. This lever is pivoted at 43 on sound box 3 and carries at its other end a stylus 45.

The stylus 45 travels in a groove 47 of the hill and valley type and formed in the record member 15 alongside of and parallel to the groove 13. The groove 47 may be formed in the master record of which the record 15 is a reproduction by any suitable means; it may be cut by manually operated means or by automatic mechanism acting in conjunction with the ordinary record forming mechanism in response to the sounds being recorded, as described more in detail in my copending application, Serial No. 210,847, for method of and apparatus for recording and reproducing sound, filed January 8, 1918.

Although the variations in depth of the groove 47 are necessarily slight, the multiplying effect of the lever 41 and of its connection to the shaft 31 causes the cone 33 to be rotated through considerable angles as the point of the stylus 45 travels over the undulations of the groove 47, and the effective size of the slots 27 accordingly varies between relatively wide limits. As the volume of sound which passes from the sound box 3 into the horn 7 depends upon the effective size of the slots 27, it will be seen that this

2

arrangement provides a simple and effective means of modifying, according to predetermined plan, the rendering of a selection. Since the undulations of the groove 13 and those of the groove 47 are integrally connected as parts of the record member 15, the operation of the modifier is in exact time relationship with the operation of the diaphragm 1, and the difficulties and inaccuracies of manual control of the sound modification are avoided. Obviously the stylus 45 may, if desired, be removed and the automatic control of the sound modifier dispensed with. Between the conical members 25 and 33, but not covering the slots 27, is fitted a packing 34 which reduces the transmission of sound from the sound box to the horn through the material of the members 25 and 33.

20 The pin and slot arrangement 21, 23 permits the adjustment of the member 25 so as to accommodate the modifier to records in which the grooves 13 and 47 are of different relative average depths, for it is evident that the member 33 will not be rotated to the same positions by the undulations in the groove 47 when that groove as a whole is deeply cut, in comparison with groove 13, as by similar undulations in a relatively shallow groove. A shifting of the range of automatic adjustment of the modifier will likewise be produced by a change of the relative lengths of the portions of styli 11 and 45 which project from their respective holders, such as may readily occur, for instance, when a worn stylus is replaced; such shifting may also result from the wearing or other changes of the different parts of the operating mechanism. As a means of accomplishing the adjustment of the member 25 the member 21 is provided with a combined handle and index scale 49 which projects through the slot 51 in the wall of the sound box 3 and over which extends the finger 53 carried by the conical member 33. When, with the stylus 45 in a neutral position in the groove 47, the finger 53 is at one side of the arrow on the member 49, the latter member, and consequently the member 21, should be adjusted until the arrow and finger are in alinement. This arrangement also affords a means by which different modifying effects may be obtained from a given groove 47 by moving the member 53 to the right or left of the central arrow on the scale member 49.

60 This invention, as will be apparent from the above description, may be variously utilized for the modulation of reproduced sound. A specific instance is in connection with the reproduction of selections in which, for example, loud orchestral passages alternate with vocal passages; the general effect of the selection will, under many circumstances, be improved if the variations of

loudness in the reproduced piece are less extreme than in the original rendition.

What is claimed is:

1. In combination, a sound conveyer, a record, a sound box intermediate the conveyer and record, a sound modifier within the sound box, an automatic means controlled by said record for adjusting the modifier. 70

2. In combination, a sound chamber, a sound modifier within said chamber, means for automatically adjusting said modifier, and means for manually adjusting said modifier to correspond to a shifting of the range of adjustment of said first named means. 75

3. In combination, a sound conveyer, a record, a sound box intermediate the conveyer and record, a sound modifier regulating the passage of sound waves from the sound box to the conveyer, and means controlled by the record for automatically adjusting the modifier. 85

4. In combination, in a phonograph or the like, sound producing means, a sound chamber leading from said sound producing means, a valve in said chamber, and record actuatable means for controlling the position of said valve. 90

5. In combination, a sound conveyer, a record, a sound box intermediate the conveyer and record, record actuatable means to effect sound production by the sound box, and record actuatable means to vary the proportion of the sound produced by the sound box which is transmitted to the sound conveyer. 95

6. In a phonograph, a sound producing diaphragm, a diaphragm chamber, a sound conveyer, an adjustable modifier within the chamber to control the proportion of sound produced by the diaphragm which is transmitted from the diaphragm chamber to the conveyer, and record actuatable means for automatically adjusting the modifier. 105

7. In combination, in a phonograph or the like, a sound producing mechanism, mechanism for variably modifying the sound after it is produced, and a record member having two parallel spiral grooves for operating said sound producing mechanism and said sound modifying mechanism respectively, said grooves arranged radially alternate on said record member. 115

8. In combination, a sound producing mechanism, a sound conveyer, adjustable means to vary the proportion of sound produced by the sound producing mechanism which is transmitted to the sound conveyer, and automatic means for changing the adjustment of the first mentioned means. 120

9. In combination, sound producing mechanism, a chamber therefor, a sound conveyer leading from the chamber, a sound modifier in the chamber, means for operat- 125

- ing the sound producing mechanism, and means operatively connected with the first means for simultaneously adjusting the modifier.
- 5 10. In combination, a sound conveyer, a sound box having an opening through which communication is provided between the conveyer and sound box, the latter also having a flanged portion surrounding the sides of
- 10 the opening, a pair of members covering the opening, each having one or more openings; said members being relatively movable to vary the extent of registration between the one or more openings in one member and the one or more openings in the other members ¹⁵ and one of the members being adjustably mounted on the flanged portion to vary the normal extent of said registration, and means to effect movement of the other member to vary the registration from the normal ²⁰ extent thereof.

In witness whereof, I hereunto subscribe my name this 9th day of March A. D., 1918.

JAMES L. McQUARRIE.
